ELECTRIC HIGH-PRESSURE DISCHARGE
TUBE

Willem Elenbaas, Eindhoven, Netherlands, assignor to General Electric Company, Schenectady, N. Y.

Application March 30, 1946, Serial No. 658,409
In the Netherlands August 13, 1942Section 1, Public Law 690, August 8, 1946
Patent expires August 13, 1962

6 Claims. (Cl. 176—126)

1

My invention relates to electrode structures, and more particularly to electrode structures for high pressure electric discharge devices such as high pressure electric lamps.

It is common to equip high-pressure discharge tubes (i. e. discharge tubes wherein the pressure during normal operation has such a value that the discharge is contracted) with incandescent electrodes consisting of a core coated with a layer of a substance having a high electron-emitting capacity, which layer often entirely or partly consists of alkaline earth oxides. These incandescent electrodes are usually not heated by a separate heating current, but exclusively by the discharge so that only one supply conductor is required for each electrode. In many cases such an electrode is nevertheless provided with two supply conductors, of which only one is used during operation or which are electrically interconnected.

The core of this incandescent electrode consists of metal (as a rule of a refractory metal such as tungsten) and is frequently helically wound. Furthermore, it is known to wind a second wire helically on a metal wire, the assembly being helically wound again. In this way a solid assembly can be obtained which is adapted to be secured only by one end to a supporting wire, the axis of the helix coinciding with the axis of the discharge tube. After that the cores thus formed, as has already been stated above, are coated with a layer having a low work function (less than three volts).

The invention concerns high-pressure discharge tubes having one or more incandescent electrodes that are heated solely by the discharge during normal operation and consist of a metal core coated with a substance having a high electronic emitting capacity. The invention purports to improve these discharge tubes, more particularly as regards the incandescent electrodes available therein.

According to the invention the core of these electrodes is shaped as a band and is so folded as to form a reentrant part containing the substance having a higher electron-emissive capacity.

In order to be able to emit a sufficient quantity of electrons the emitting substance of an incandescent electrode, which is not separately heated, must be heated to the required temperature by the discharge which in high-pressure discharge tubes acts only at a comparatively small part of the cathode. This is accompanied by a certain cathode drop i. e. a voltage loss just

2

before the incandescent electrode. If the heat evolved where the discharge acts is rapidly carried away from this point this involves a higher cathode drop which means not only an increase in loss of energy but also a strong disintegration of the electrode.

When the core of the incandescent electrode in the discharge according to the invention is shaped as a band the dissipation of heat through this core can be made very low. In fact, it has been found that the section of the band-shaped core can be made very small whilst ensuring a sufficient rigidity of the electrode. Generally the thickness in microns of the band-shaped core should be made smaller than 100 times the operating current strength in amperes; the width of the band-shaped core being made equal to at least 10 times the thickness. Since the band-shaped core, to which as such the emitting substance cannot easily be secured in a sufficiently rigid manner, is provided with a reentrant part a more or less pocket-shaped part is formed in which the emitting substance can be easily introduced in a sufficient quantity.

Moreover, the electrode has a low weight so that the risk of breaking of the electrode from the supporting wire to which it is attached, which sometimes occurs in transporting the discharge tube, is but small. In addition the cost of manufacture is low.

The invention will be more fully explained by reference to the drawing representing, by way of example, one embodiment thereof.

In Fig. 1 the reference number 1 designates a high-pressure mercury-vapour discharge tube made from hard glass or quartz.

Each end of the tube contains an electrode 2 which is represented in perspective in Fig. 2. The core of this electrode consists of a strip of tungsten having a thickness of 0.1 mm., a width of 5 mms. and a length of 20 mms. This strip is folded in the form of a heart having a reentrant part 3 containing the electron-emissive substance 4 consisting, for instance, of alkaline earth oxide (more particularly barium and/or strontium oxide) mixed, if required, with other substances such as, for instance, strontium oxide and quartz powder. Both ends of the tungsten strip, which with its flat side is positioned perpendicularly to the axis of the tube, are secured to a lead-in conductor or wire 5 which is sealed into the wall of the tube with the interposition of a bead 6. The folded strip of electrode 2 in the embodiment shown in Figs. 1 and 2 is provided with a re-entrant part forming a substantially cylindrical-

shaped groove which is transverse to the axis of the arc discharge path.

The discharge tube is filled with a rare gas, for instance, argon, at a pressure of 4 mms. and furthermore contains a quantity of mercury which is small so that the mercury vapour, after the tube has attained its state of equilibrium, is unsaturated. In this rare gas mercury-vapour atmosphere a high-pressure discharge takes place, the vapour pressure amounting to about 1 10 atmosphere. The tube which may be used for the emission of visible light or ultraviolet rays and has an internal diameter of 25 mms. and a distance between the electrodes of 100 mms. is fed from an alternating current supply and operated with a current strength of 2.5 amps., the voltage difference between the electrodes then being 120 volts.

The shape of the electrodes may be different from that represented in Fig. 2. Fig. 3, for instance, represents another shape which is also very practicable.

The electrodes used in the tube have a low weight and can be easily shaped, whereby the manufacture of the electrodes and consequently of the tube is rendered cheap. The dissipation of heat from the point where the discharge acts is very low owing to the tungsten strip.

What I claim is:

1. In a high pressure arc discharge device comprising spaced electrode structures for sustaining an arc therebetween, at least one of said electrode structures comprising a lead-in conductor and a folded strip of thin refractory metal supported by said conductor and having a re-entrant part forming a groove extending laterally across the strip and facing the arc path and transverse thereto, and electron-emissive material in said groove.

2. In a high pressure arc discharge device comprising spaced electrode structures for sustaining an arc therebetween, at least one of said electrode structures comprising a lead-in conductor and a folded strip of thin tungsten supported by said conductor and having a re-entrant part forming a groove extending laterally across the strip and facing the arc path and transverse thereto, and an electron-emissive material comprising an alkaline earth oxide in said groove.

3. In a high pressure arc discharge device comprising spaced electrode structures for sustaining an arc therebetween, at least one of said electrode structures comprising a lead-in conductor and a folded strip of refractory metal hav-

ing a thickness of 0.1 mm. supported by said conductor and having a re-entrant part forming a groove extending laterally across the strip and facing the arc path and transverse thereto, and electron-emissive material including an alkaline earth oxide in said groove.

4. In a high pressure arc discharge device comprising spaced electrode combinations for sustaining an arc therebetween, at least one of the electrode combinations comprising a lead-in conductor, a folded strip of refractory metal having a re-entrant part forming a groove extending laterally across the strip and facing the arc path and transverse thereto, the thickness of said strip in microns being less than 100 times the discharge device operating current in amperes and the width of said strip being at least 10 times the thickness thereof, and electron-emissive material in said groove.

5. In a high pressure arc discharge device comprising spaced electrode structures for sustaining an arc therebetween, at least one of said electrode structures comprising a lead-in conductor and a folded strip of thin refractory metal supported by said conductor and having a re-entrant part forming a substantially cylindrical-shaped recess extending laterally across the strip and transverse to the arc path, and electron-emissive material in said recess.

6. In a high pressure arc discharge device comprising spaced electrode structures for sustaining an arc therebetween, at least one of said electrode structures comprising a lead-in conductor and a folded strip of thin refractory metal secured at both ends to said conductor and having intermediate its ends a reentrant part forming a groove extending laterally across the strip and facing the arc path and transverse thereto, and electron emissive material in said groove.

WILLEM ELENBAAS.
